UNITED STATES PATENT OFFICE.

FRANCIS A. KERSHAW, OF KENOSHA, WISCONSIN.

DESIGN FOR A FRAME FOR BICYCLES.

SPECIFICATION forming part of Design No. 27,551, dated August 17, 1897.

Application filed May 24, 1897. Serial No. 637,962. Term of patent 14 years.

To all whom it may concern:

Be it known that I, FRANCIS A. KERSHAW, a citizen of the United States, residing at Kenosha, in the county of Kenosha and State of Wisconsin, have invented and produced a new and useful Design for Frames for Safety-Bicycles, reference being had to the accompanying drawing, forming a part hereof.

In the accompanying drawing the figure is a perspective view of my design.

The leading feature of my design consists, essentially, in a frame portion, which is provided with tubular members connected to a lower circular central cup-shaped portion, the end of one of the lower members having two cup-shaped portions at right angles to each other.

A A are the tubular members of the main frame portion; B B', the lower-extending tubular members; C, the lower central circular cup-shaped portion, and D D' the cup-shaped portion on the rear end of the lower-extending tubular portion B', and arranged at right angles to each other, the whole presenting to the eye a harmonious and ornate figure, as shown in the accompanying drawing.

I claim—

A design for a frame for safety-bicycles as herein shown and described.

FRANCIS A. KERSHAW.
